In Germany May 4, 1933

25 Claims. (Cl. 112—21)

The present invention relates to sheet feed devices for use in placing folded sheets or book sections straddlewise upon a pivotal sheet carrier such as the reciprocatory stitching saddle of a stitching machine for assembling and stitching books or book-pads in which, as is well known to those skilled in the art, the stitching saddle is pivotally mounted and adapted to assume alternately a work laying-on position and a stitching position beneath the stitching means which hereinafter will be referred to for the sake of convenience as the open and closed positions of the saddle.

In the operation of machines of this type the work, hereinafter referred to as the folded sheet, usually is fed to the sheet carrier or saddle by hand or mechanically when the saddle is in the open position and the latter thereupon is moved to the closed position beneath the stitching means so that the folded sheet is attached to the previously stitched book or book-pad. In the subsequent movement of the saddle to the open position the last stitched sheet thus is retained in its stitching position and the saddle performs an idle movement to the open position. To expedite the production of the machine it is essential to return the saddle to the open position with all possible speed since when the saddle is in the stitching position and also when moving to and from this position the sheet laying-on operation is suspended. On the other hand the length of time taken for each laying-on operation, when the latter is performed with the saddle stationary in the open position, obviously is a limiting factor in the output of the machine, the other limiting factor of which is the safe speed with which the saddle may, in practice, be oscillated.

It is already known to extend the time of the work laying-on period in any given speed of revolution of such machines by using a rigid auxiliary table constantly stationary in the lowermost or open position of the feeding and stitching saddle and from which the signature is progressed to the saddle when the latter is in the open position. In spite of acceleration of the speed at which the signature is transferred to the stitching saddle the latter remains for comparatively long periods in the open position and in addition very complicated arrangements are involved for receiving and registering the signatures thus laid on the saddle.

Also, in book stitching machines it has been already proposed to use instead of the usual pivotal feed saddle a saddle of double length moving to and fro laterally beneath the stitching

means, the signature first being positioned on the end of this saddle remote from the stitching means against a stationary stop on the wall of the machine; the folded sheet abuts the stop whereas the saddle slides through beneath both the stop and the sheet when it is withdrawn from the last stitched sheet, thus bringing the unstitched sheet to the opposite or stitching end of the saddle. In the return motion of the saddle the newly applied signature is carried with it beneath the needles. The last mentioned arrangement in practice could not successfully be used for stitching together a number of signatures to form a book or book-pad.

The object of the present invention is to provide an improved sheet feeding arrangement which possesses the advantages of both known arrangements without involving their disadvantages.

According to the present invention provision is made of a sheet feed device comprising an auxiliary sheet carrier or saddle associated with the main sheet carrier or stitching saddle and adapted to move therewith while a folded sheet is transferred from the auxiliary carrier to the main carrier by means of a displaceable sheet-engaging member.

In one form of the invention the main carrier or saddle may be extended to form the auxiliary carrier or saddle which thus participates in the pivotal motion of the main saddle, while in a second form of the invention the auxiliary saddle may be separately mounted so as to move with the main saddle through only part of the travel of the latter. The entire cycle of the stitching operation can in consequence be utilized for laying-on the new folded sheet. The sheet is not however abruptly thrown on to the stitching saddle but the sliding over from the auxiliary carrier or saddle to the main saddle may extend over almost the entire reciprocatory movement of the main saddle. An interval of rest for the stitching saddle in the open position is no longer necessary but despite the rapid oscillation thereof which the present invention renders possible the sheets are carefully slid up to the limiting stops on the main saddle.

The sheets preferably are transferred from the auxiliary saddle to the main saddle by a mechanically actuated gripper the return motion of which can occur during the stitching because the gripper itself slides through beneath the newly applied sheet. This motion also may be comparatively slow because approximately the entire reciprocatory movement of the main saddle is avail-

able for the completed movement of the gripper. It is not necessary for there to be an interval of rest in the open position of the main saddle while at the same time the laying-on period is not limited to the open position of the auxiliary carrier or saddle. It may extend over the entire period of rotation of the machine because a further signature may be applied to the auxiliary saddle without obstructing the movement of a signature previously applied thereto and yet to be fed to the main saddle.

When laying the signature on the saddle the operator can sit in front of or at the side of the machine. In the first case which permits a better supervision of the stitching operation the amplitude of the swinging motion of the main saddle constitutes a certain limitation of production in spite of the fact that the travel of the saddle can be kept very appreciably smaller than hitherto where a wide opening of the saddle facilitated the smooth laying on because the signature is now no longer laid on in the open rest position of the saddle. It lays within the scope of the present invention still further to limit this travel which in the case of the main saddle must have a certain minimum value in order to be able to strip off from the point of the saddle the forwardly directed stitched half of the signature which lies on the saddle. To this end the auxiliary saddle is arranged so as not to perform the complete stroke of the main saddle but to pivot only in part therewith and thus for example is brought to rest in a sheet receiving position before the main saddle reaches the stitching position with the last received sheet. In this way its travel is reduced and the laying-on is facilitated but care must be taken that the transfer of the signature to the main saddle does not occur until the opening motions of the two saddles again correspond which is possible without loss of time because in any case the new signature can only pass to the main saddle when the previous signature has been stripped therefrom. This cannot occur until the commencement of the opening of the machine. Fundamentally this reduction of the travel of the auxiliary saddle could also occur in the open position of the saddle—position of the saddle downwardly. This requires only a correspondingly different distribution of the slide motion of the feed saddles. In order to attain this partial separation of the auxiliary saddle from the main saddle, the former must be provided with a separate drive control and the point of pivotatation must preferably coincide with that of the main saddle.

The gripper or slide member which transfers the signature during the time of opening of the book stitching machine may be of any desired construction. Preferably it is so arranged that its return motion does not interfere with the laying on of a new signature on the auxiliary carrier or saddle so that it passes through beneath it into its initial position. The inventive idea is not limited to machines in which the feeding is effected manually. It may equally advantageously be applied to machines with automatic sheet feed. In this case the signature is applied by any suitable device to the auxiliary carrier or saddle preferably in the fully open or rest position thereof and is then transferred.

In order that the invention may clearly be understood, two constructional forms thereof will now be described with reference to the accompanying drawings, in which:

75 Figs. 1 and 1a are elevational views of a book

stitching machine of the swinging stitching saddle type commonly used to produce continuously stitched book pads, the machine being modified in accordance with the present invention.

Fig. 2 is an elevational view taken at right angles to Fig. 1 and looking in the direction of the arrow A.

Figs. 3, 4, 5, 6 and 7 are detail views, drawn to a larger scale, of the sheet displacing means associated with the auxiliary sheet carrier or saddle, 10

Figs. 8, 9 and 10 are detail views, drawn to a larger scale, showing the arrangement and several steps of movement of the sheet registering and retaining means associated with the main carrier or stitching saddle, 15

Fig. 11 is an elevational view of an alternative arrangement of the main saddle and auxiliary saddle according to the present invention in which the saddles are divided and perform associated but independent movements, while 20

Fig. 12 is a view taken at right angles to Fig. 11 and looking in the direction of the arrow B.

Referring now to Figs. 1 and 2, the machine frame generally designated by the letter F includes upright supporting members 12, 13 and 14 25 which support a bearing shaft 28. Arms 39, 39a rotatably mounted upon the shaft 28, carry at the free extremities thereof a stitching saddle S which is oscillated between the closed or stitching position beneath known thread stitching 30 means T and the open or work receiving position indicated by chain dotted lines in Fig. 2. A positively driven cam shaft 11 also journaled in the frame uprights 12, 13 and 14 and driven through known driving means (not shown) carries cam 35 grooved discs 61 which engage cam followers 62 carried by suitable extensions of the arms 39, 39a thus to impart reciprocatory movement to the saddle S in the rotation of the shaft 11 and cam 61 which, in known manner, are timed in accordance with the actuation of the stitching means. The mechanism so far described is that of the known stitching machines of this type, but in the present construction the saddle S is provided at the left hand side thereof, as viewed in Fig. 1, with an extension or auxiliary saddle S' which is at least equal in length to the saddle S so that in practice the work carrier or saddle S, S' is approximately double the normal length of the saddles in such stitching machines. One extremity of the auxiliary saddle S' is rigidly connected to the corresponding end of the saddle S while the other extremity of the saddle S' is supported by the arm 39b which is pivotally mounted upon the shaft 28. The auxiliary saddle 55 thus joined to the saddle S and pivotally supported so as to move about the axis common to the last mentioned saddle partakes of the movement of the latter to and from the work stitching position as above described.

The work to be stitched, e. g. an opened folded sheet, is initially laid upon the saddle S' either manually or by automatic sheet feeding means of any suitable type and is moved from the auxiliary saddle to the main or stitching saddle by 65 displaceable sheet engaging means. These means, as shown in the present construction, comprise a pusher device P (Figs. 1 to 7) which includes a carriage or slide member 53 adapted freely to slide upon the outer inclined faces of the saddle S' and 70 retained in position thereon by means of a flange piece 53a which engages the apex or ridge of the saddle S' as shown more particularly in Figs. 4 and 5.

The slide 53 carries a flat bar 54 which is ad- 75

justably mounted in a slot in the former member and secured therein by means of a set screw 53b in such manner as to lie in contact with the face of the saddle and extending longitudinally thereof. The free extremity of the bar 54 is bevelled as shown in Fig. 3 while a blade spring 55 is secured to the upper surface of the bar. The under-surface of the spring 55 is offset from the surface of the bar 54 and is provided with a shoulder piece 59 which normally is urged by the spring 55 into contact with the bar while some part of the shoulder 59 overhangs a lateral edge of the bar as shown in Fig. 5. A sheet strap or block 47, secured to the upper surface of the bar 54, is located immediately behind the shoulder 59. An arm 21 secured to, and extending downwardly from, the slide 53 is bifurcated at its free extremity to connect with driving means, hereinafter described, whereby the sheet displacing or pusher device P is reciprocated longitudinally of the auxiliary saddle S'.

A stationary deflecting member 56, positioned in the path of travel of the overhanging portion of the shoulder 59 as shown in Figs. 3, 4, 5, 6 and 7 is supported by an arm 57 which is adjustably mounted upon a rod or bar 58, the latter being positioned to the rear of the saddle S' and substantially parallel therewith. The deflecting member 56 has its upper surface cammed so that when the pusher device P is advanced in the direction of the arrow 64 (Fig. 3) the shoulder 59 contacts with the cammed surface of the member 56 and is lifted from the bar 54. The base of the arm 57 also carries an abutment or stop 40 which extends into a slight valley in the back plate of the saddle S' thus to form a sheet-lay against which abuts an edge of the folded sheet placed upon the saddle S'. The sheet stop or lay 40 if desired could be mounted directly upon the rear saddle. A ramp or plow 50 is secured to the rear edge of the slide member 53 and extends longitudinally of the front plate of the saddle S'. The member 50 is arranged so that its free extremity contacts with the saddle plate as shown or, if desired, enters a slot extending longitudinally of the saddle plate and serves to lift the forward edge of a sheet laid upon the saddle S' thus to permit the pusher device P to slide beneath the sheet in its reciprocatory movement to the position shown in chain dotted lines in Fig. 1.

The pusher device P is adapted to move longitudinally of the auxiliary saddle S' in a reciprocatory movement from the position shown in full chain dotted lines in Fig. 1 to that shown in full lines in Fig. 1a. To effect this movement which obviously must be timed in accordance with the movement of the main saddle S an eccentric disc 15 provided with a groove 15a is mounted fixedly upon the shaft 11. A strap 16 provided with a slot adapted loosely to embrace the shaft 11 carries a follower roller 16a which engages the groove 15a so that in the rotation of the disc 15 the strap 16 is reciprocated in a substantially vertical direction. The lower extremity 16b of the strap 16 passes through a guide block 65, which is secured to a convenient frame member, and carries a substantially horizontal slotted plate 66 which is loosely connected by means of a pin 67 with the slotted, free extremity of a pivotal lever 17. The further extremity of the arm 17 is fixedly secured to a substantially horizontal rocking shaft 68 supported in bearing brackets 69, to which is also fixedly secured the lower bossed or sleeved extremity of an upwardly extending lever 18. The upper extremity of the lever 18 is ad-

justably coupled by means of a pivotal rod 19 to a slide block or carriage 20 which slides upon a pair of stationary, parallel guide rails 23, 24, the latter extending substantially parallel with the auxiliary saddle S' and supported at their extremities by a bearing bracket 51 on the machine frame member 13 and the bearing bracket 25 secured to the frame upright 14. The slide member 20 is linked to the pusher slide 53 by means of a rod 22 which is secured at its lower extremity to the slide member 20 while its upper portion engages the forked arm 21 to effect a loose coupling. The rod 22 is shaped in a curvature which has its radius upon the axial line of the shaft 28 i. e., the pivotal axis of the saddle S and auxiliary saddle S' so that the forked arm 21 freely slides upon the rod 22. Thus in the rotation of the shaft 11 to effect the operative movement of the saddle S the pusher device P is reciprocated longitudinally of the saddle S' and in timed relation to the operative cycles of the machine.

In order that the sheets fed by the pusher device P from the auxiliary saddle S' to the main saddle S may appropriately be retained upon the latter in the correct stitching position the machine is provided with a mechanically operated sheet retaining device. As shown in Figs. 1, 2, 8, 9 and 10, this consists of a lever 27 pivotally mounted at its lower extremity upon the shaft 28 and extending upwards to a point above the arcuate path of travel of the saddle S. The upper extremity of the lever 27 is formed with horizontal bearing brackets 27a in which is journaled a rocking shaft 29, the latter extending parallel with the saddle S and having fixedly secured thereto a rocking lever 30 and resilient sheet retaining fingers or blade springs 26, all of which are secured to the rocking shaft in an adjustable manner as by set screws (not shown). The lever 27 is provided with a buffer 27b which is positioned intermediate the length of the lever to engage a similar buffer 40 projecting from the saddle supporting arm 39 as shown in Fig. 8, the arm being resiliently urged to assume this position by means of the helical tensile spring 38. At its upper extremity the lever 27 is provided with a second buffer or stop 44 which is arranged to engage a corresponding buffer or stop 43 secured to a stationary member of the machine frame. The engagement of the buffers or stops 43, 44 takes place when the main saddle S is moved to the stitching position as shown in Fig. 1 and hereinafter described.

The free extremity of the rocking lever 30, provided with a trailer or cam follower roller 31, is constantly urged upward or in an anticlockwise direction of rotation about the axis of the shaft 29 by means of the helical tensile spring 34 so that the cam follower 31 is held resiliently in engagement with the under-cammed face 32 of the guide strip 35 or the under-cammed face 33 of the deflecting strip 36 according to the operative movement of the arm 21. The cammed guide strip 35 is rigidly secured to a vertical support 35a rising from the frame of the machine, as shown in Fig. 2, while the deflecting strip 36 is secured to the foot of an L-shaped bracket 36a which is pivotally mounted upon a stub shaft 37 journalled in a bearing bracket 37a the latter being secured at the upper extremity of the frame member 35a. A helical tensile spring 46 anchored at its extremities to pins rigidly secured to the strip 35 and stub shaft 37 respectively urges the bracket 36a and strip 36 to rotate in clockwise 75

direction about the axis of the shaft 37 so that the free extremity of the strip 36 is normally held against the cam face 32 at the point indicated by the reference 45a while that extremity 5 of the strip 36 which is secured to the bracket 36a lies apart from the cam face 32 readily to permit the entry therebetween of the follower roller 31 in the anticlockwise movement of the arm 27. The sheet retaining blade springs 26 10 being rigidly secured to the shaft 29 are urged downwards resiliently to engage the apex of the saddle S or a folded sheet placed straddlewise thereon which engagement occurs when the saddle S is travelling to the closed or stitching position 15 and is maintained until shortly before the saddle completes the closing movement.

Sheet engaging springs 41 (Figs. 1, 2, 8, 9 and 10) co-operate with the sheet retaining members 26. The springs 41 are secured to a bar 10 20 which extends parallel with the saddle S and is held above the latter by means of curved arms 42 which are rigidly supported by brackets attached to suitable members of the machine frame. The resilient springs 41 thus extend downwards 25 into the path of travel of the apex of the saddle S so as resiliently to engage the sheet carried thereon and wipe thereover in a manner which serves to retain and smooth the sheet upon the saddle as it finally is carried to the stitching position 30 (Fig. 2).

The operation of this constructional embodiment of the invention is as follows:

The work, such as a folded sheet or book signature, to be stitched is opened and placed either 35 manually or by automatic sheet-feeding means upon the auxiliary feeding saddle S' and drawn to the left against the work-lay or stop 10. Assuming that the sheet displacing or pusher device P is in its position to the extreme left and slightly beyond the work lay 10 as shown in chain dotted lines in Fig. 1 and in full lines in Figs. 3, 4 and 5 the pusher member P now commences to move to the right to engage and displace the sheet. The laterally overhanging portion of the shoulder 59 almost immediately rides up on to the cam rise of the deflecting member 56 so that the entire shoulder piece 59 and the free extremity 40 of the blade spring 55 are lifted to permit the adjacent edge of the sheet now on the saddle to pass between the shoulder 59 and the bar 54 and so abut the stop 47 in the movement of the pusher device P to the right.

When the sheet is thus positioned the overhang 55 of the shoulder 59 passes beyond the deflecting member 56 and urged by the spring 55 the shoulder descends to clamp the sheet against the bar 54 as shown in Figs. 5 and 7. In the continued movement of the pusher device P to the right, which may be effected during the movement of the empty stitching saddle S either to the open or closed position, the sheet or signature held thereby is displaced in a sliding motion and transferred to the stitching saddle, the position of the sheet upon the saddle S being determined by the amplitude of the stroke of the pusher device P which is adjustable and is adjusted according to the size of the work to be positioned beneath the thread stitching means T.

When the sheet is transferred to the saddle S and the latter lies in the extreme open position, the cam follower 31 attached to the rocking arm 30 is positioned at the tail end of the cammed guide 35 so that, as shown in Fig. 8, the sheet retaining springs 26 are held away from the apex

of the saddle. Since the arm 27 and rocking arms 30, through the resilient linkage of the spring 38, are carried forward in the closing movement of the saddle S, the cam follower 31 is drawn along the cammed face 32 to the valley 45, the deflecting member 36 yielding outwards to its passage, thereby permitting the blade springs 26 to be drawn down by the helical spring 34 to clamp the sheet upon the saddle as shown in Fig. 9. The sheet is now securely held upon the saddle in the position determined by the pusher device P, while the saddle continues its movement to the closed or stitching position. Prior to the closing of the saddle to the stitching position the cam follower 31 moving with the lever 27 leaves the cam valley 45 and rides upon the portion 45a of the cammed face 32 thus lifting the retaining springs away from the saddle S and sheet carried thereon. Immediately following the upward movement of the springs 26 the buffer 44 carried by the lever 27 encounters the stationary buffer 43 (Fig. 2) so that the lever 27 is withheld from further movement with the saddle S which extends the spring 38 in completing its movement to the stitching position. Coincident with or immediately before the release of the springs 26 from the saddle S the latter encounters the sheet engaging or smoothing spring fingers 41 which as above described retain and smooth the sheet upon the saddle. Thus held in correct and pre-determined stitching position the sheet is conveyed by the saddle S to the final stitching position and stitched to the book pad.

The movement of the cam follower 31 to the cam face 45a permits the free extremity of the deflecting member 36 to move into contact with the cammed member 35 thus to deflect the follower 31 from the cam valley 45 and cause it to travel along the cammed surface 33 of the deflecting member 36 in the return movement of the saddle S to the work receiving or open position. In this manner the springs 26 are held raised from the saddle S until the next sheet is fed thereto by the pusher device P which has meanwhile been returned to its position to the left as shown in Fig. 1. The return of the pusher device may be effected after the next sheet is placed upon the auxiliary saddle S' since by reason of the plow piece 50 the slide 53 will lift the forward edge of the sheet thus enabling the entire pusher device P to pass beneath the signature to the left hand position. It will be clear from the above description that the time taken for the entire cycle of the machine is made available to the operator for laying work upon the auxiliary saddle S' while the transfer thereof from the auxiliary saddle to the main saddle can be effected at any point of the opening or closing movement of the empty saddle.

A second constructional embodiment of the invention as shown in Figs. 11 and 12 differs from the first construction above described in that the common pivotal motion of the main and auxiliary saddles S, S' does not extend over the entire travel of the main saddle but only over some part of the closing movement of the latter. Despite the increased rate at which the cycle of a stitching machine constructed according to the present invention may be performed it has been found that the transfer of the signature may be effected efficiently in less time than that occupied in the full reciprocation or operative cycle of the stitching saddle in its opening and closing movement. Therefore it is possible to limit the extent of movement of the auxiliary saddle S' so that the

operator can conveniently sit in front of the machine and lay the work upon the auxiliary saddle during the entire in and out swing of the auxiliary saddle without the extreme motion of the operator's arms which is necessary to accommodate the full movement of the main or stitching saddle.

To this end the saddles S and S' are separately mounted upon the common pivotal shaft 28; the main or stitching saddle S being actuated in a manner exactly similar to that described in the first embodiment, through the medium of the cam grooved discs 61 mounted upon a drive shaft 11 and cam followers 62 carried by extensions of the saddle supporting arms 39, 39a and adapted to engage the cam grooves of the rotatable discs 61 to impart a pivotal reciprocatory movement to the main saddle S in known manner. In this embodiment however the separately mounted auxiliary saddle S' is positioned to the right hand side of the machine as viewed in the drawings and swinging movement about the pivotal shaft 28 is imparted thereto by means of a cam 48 the contour of which corresponds to that of the cam grooves in the discs 61 but to a reduced scale and set eccentric thereto so that the throw of the saddle S' corresponds to that of the main saddle S in respect of the lower or approaching fully open part of the travel of the latter but is greatly reduced in extent during the full closing movement of the main saddle. The auxiliary saddle S' is supported by an arm 11 secured at its lower extremity to a sleeve or bearing collar 11a which is journaled upon the shaft 28 and to which is also rigidly attached an arm 12 carrying a cam follower 13, the latter being held in engagement with the cam 48 by means of a helical tension spring 14. The saddle S' is equipped with a sheet displacing device P, while the saddle S is equipped with sheet retaining springs 26 and sheet retaining and smoothing springs 41, all of which are precisely similar in construction and operation to the members of this description in the first embodiment.

The operation of this embodiment of the invention also is similar to that of the first embodiment excepting that the auxiliary and main saddles are moved independently and to the different degrees shown in Fig. 12. In travelling from the open to the closed position the main or stitching saddle S moves from the position shown in chain dotted lines to that shown in full lines whereas the movement of the auxiliary saddle S' is within the limits as indicated by dotted and full lines in Fig. 12. Within this limited travel of the saddle S the auxiliary saddle is in precise register therewith so that the transfer of the sheet from the saddle S' to the saddle S may be performed prior to the latter attaining the fully opened position or during its return to the stitching position. As in the first described embodiment the placing of a sheet upon the auxiliary saddle may overlap the transfer of the one previously laid thereon.

Moreover, the curtailed movement of the auxiliary saddle may be effected in the upper portion of the travel of the main saddle instead of the lower portion which to some extent is a reversal of the last described arrangement but could be made effective when the feed of the sheets is achieved from an adjacent magazine.

It will be obvious that by the suitable adjustment of the several sheet handling members above described folded sheets or other work of various

sizes may readily be dealt with in the manner set forth.

We claim:

1. A book stitching machine which includes stitching means, a main pivotal sheet carrier arranged to move to and from said stitching means, an auxiliary sheet carrier arranged to move with said main sheet carrier, a sheet-engaging device associated with said carriers, and means for displacing said sheet-engaging device relatively to said carriers so that a sheet laid upon said auxiliary carrier is engaged by said device and transferred to said main carrier during the movement of said carriers.

2. A book-stitching machine which includes stitching means, a main pivotal sheet carrier arranged to move to and from said stitching means, an auxiliary sheet carrier arranged to move with said main sheet carrier, a sheet-engaging device, and means for reciprocating said sheet-engaging device longitudinally of said sheet carriers so that a sheet laid upon said auxiliary carrier is engaged by said device and transferred to said main carrier during the movement of said carriers.

3. A book stitching machine which includes stitching means, a main pivotal sheet saddle arranged to move to and from said stitching means, an auxiliary sheet saddle arranged to move with said main sheet saddle, a sheet-engaging device slidably mounted upon said auxiliary sheet saddle, and means for reciprocating said sheet engaging device longitudinally of said auxiliary saddle so that a sheet laid upon said auxiliary saddle is engaged by said device and transferred to said main saddle.

4. A book stitching machine which includes stitching means, a main pivotal sheet saddle arranged to move to and from said stitching means, an auxiliary sheet saddle secured to said main sheet saddle to form a lateral extension thereof, a sheet engaging device associated with said saddles, and means for displacing said device relatively to said saddles so that a sheet laid upon said auxiliary saddle is transferred to said main saddle during the movement of the latter.

5. A book stitching machine which includes stitching means, a main pivotal sheet saddle, means for moving said saddle to and from said stitching means, an auxiliary sheet saddle secured to said main saddle to form a lateral extension thereof, a sheet-engaging device slidably mounted upon said auxiliary saddle, and means for moving said sheet-engaging device longitudinally of said auxiliary saddle during the swinging movement of the latter so that a sheet laid upon said auxiliary saddle is engaged by said sheet-engaging device and transferred to said main saddle.

6. A book-stitching machine which includes stitching means, a main pivotal sheet carrier arranged to move to and from said stitching means, an auxiliary sheet carrier arranged to move with said main sheet carrier, a sheet-engaging device associated with said carriers, means for displacing said sheet engaging device relatively to said carriers so that a sheet laid upon said auxiliary carrier is engaged by said device and transferred to said main carrier, and sheet retaining means associated with said main carrier and arranged to engage and retain upon said main carrier the sheet transferred thereto.

7. A book stitching machine which includes stitching means, a main pivotal sheet carrier arranged to move to and from said stitching means, an auxiliary sheet carrier arranged to move with

- 5 said main sheet carrier, a sheet-engaging device associated with said carriers, means for displacing said sheet-engaging device relatively to said carriers so that a sheet laid upon said auxiliary carrier is engaged by said device and transferred to said main carrier, and sheet retaining means arranged to move with said main carrier to engage and retain upon said main carrier the sheet transferred thereto.
- 10 8. A book-stitching machine which includes stitching means, a main pivotal sheet carrier arranged to move to and from said stitching means, an auxiliary sheet carrier arranged to move with said main sheet carrier, a sheet-engaging device associated with said carriers, means for displacing said sheet-engaging device relatively to said carriers so that a sheet laid upon said auxiliary carrier is engaged by said device and transferred to said main carrier, sheet retaining means arranged to move with said main carrier, and means for imparting secondary movement to said sheet retaining means to engage and retain on said main carrier the sheet transferred thereto.
- 15 9. A book-stitching machine which includes stitching means, a main pivotal sheet carrier arranged to move to and from said stitching means, an auxiliary sheet carrier arranged to move with said main sheet carrier, a sheet-engaging device associated with said carriers, means for displacing said sheet-engaging device relatively to said carriers so that a sheet laid upon said auxiliary carrier is engaged by said device and transferred to said main carrier, sheet retaining means arranged to move with said main carrier the sheet transferred thereto, and a secondary sheet engaging and smoothing device arranged to contact with the sheet retained upon said main carrier.
- 20 10. A book-stitching machine which includes stitching means, a main pivotal sheet carrier arranged to move to and from said stitching means, an auxiliary sheet carrier arranged to move with said main sheet carrier, a sheet-engaging device associated with said carriers, means for displacing said sheet-engaging device relatively to said carriers so that a sheet laid upon said auxiliary carrier is engaged by said device and transferred to said main carrier, sheet-retaining means arranged to move with said main carrier, means for imparting secondary movement to said sheet-retaining means to engage and retain upon said main carrier the sheet transferred thereto, and means for controlling the secondary movement of said sheet-retaining means so that the latter are caused to release the sheet prior to the stitching of the latter.
- 25 11. A book-stitching machine as claimed in claim 10, including secondary sheet-engaging members mounted independently of the main carrier and set in the path thereof to engage the sheet borne by said main carrier in its movement to the stitching position.
- 30 12. A book-stitching machine as claimed in claim 10, including a stationary supporting member mounted above the path of travel of said main carrier, and resilient sheet-engaging fingers depending from said supporting member to engage the sheet carried by said main carrier.
- 35 13. A book-stitching machine which includes stitching means, a main pivotal sheet carrier, an auxiliary pivotal sheet carrier, driving means for moving said main carrier to and from said stitching means, separate driving means for moving said auxiliary carrier synchronously with
- 5 said main carrier over some part of the movement of the latter, sheet-engaging means associated with said sheet carrier, and means for displacing said sheet-engaging member relatively to said carriers to engage a sheet laid upon said auxiliary carrier and effect its transfer to said main carrier during the synchronous movement of said carriers.
- 10 14. A book-stitching machine which includes stitching means, a main pivotal sheet carrier, an auxiliary pivotal sheet carrier, driving means for moving said main carrier to and from said stitching means, separate driving means for moving said auxiliary carrier synchronously with said main carrier over some part of the movement of the latter and then away from said main saddle in an independent movement, and means for transferring a sheet from said auxiliary carrier to said main carrier during the synchronous movement thereof.
- 15 15. A book-stitching machine as claimed in claim 14, including sheet retaining means associated with the main carrier, and means for alternately engaging and disengaging said sheet retaining means with the sheet transferred to said main carrier.
- 20 16. A book-stitching machine as claimed in claim 14, including sheet retaining means arranged to move with the main carrier, means for imparting secondary movement to said sheet-retaining means alternately to engage and disengage the latter with the sheet transferred to the main saddle, and secondary sheet-engaging and smoothing members mounted independently of said sheet carriers and positioned to engage the sheet borne upon said main sheet carrier.
- 25 17. A book-stitching machine, which includes stitching means, a pivotal main sheet carrier arranged to move to and from said stitching means, a pivotal auxiliary sheet carrier arranged to move with said main carrier, a sheet-engaging device slidably mounted upon said auxiliary carrier, means for reciprocating said sheet-engaging device longitudinally of said auxiliary carrier during the movement of the latter so as to engage a sheet laid upon said auxiliary carrier and transfer said sheet to said main carrier during the movement of the last mentioned member.
- 30 18. A book-stitching machine as claimed in claim 17, in which the sheet-engaging device comprises a slidable carriage, sheet gripper members secured to said carriage, and means for causing said gripper members automatically to open and close in the movement of said slidable carriage thus to engage a sheet laid upon said auxiliary carrier.
- 35 19. A book-stitching machine as claimed in claim 17, in which the sheet-engaging device comprises a slidable carriage, a gripper member secured to said carriage, a sheet stop secured to said gripper member, a second resilient gripper member associated with said first gripper member and normally contacting therewith, and means for temporarily parting said gripper members so that in the displacement of said carriage the sheet on the auxiliary carrier abuts said stop and is subsequently engaged by said grippers.
- 40 20. A book-stitching machine as claimed in claim 17, which includes a sheet-engaging device comprising a slidable carriage, sheet gripper members adjustably secured to said carriage, a sheet stop carried by one of said gripper members, means for temporarily parting said gripper members to engage therewith the sheet laid upon said auxiliary carrier, a driving device mounted

independently of said auxiliary saddle, loose coupling means for connecting said slidable carriage to said driving means, and a sheet-lay associated with said auxiliary carrier independent of said sheet-engaging device.

21. A book-stitching machine as claimed in claim 17, which includes a sheet-engaging device comprising a slidable carriage, sheet gripper members secured to said carriage, a sheet stop carried by one of said gripper members, and means for temporarily parting said gripper members so that the sheet laid upon said auxiliary carrier subsequently is gripped thereby and loose coupling means for connecting said slidable carriage to said driving means comprising a slide member arranged to move longitudinally of said auxiliary carrier, means for reciprocating said slide member in accordance with the movement of the auxiliary carriage, and a curved rod which loosely couples said slidable carriage to said slide member, the curvature of said rod having its radial centre on the pivotal axis of said auxiliary sheet carrier.

22. A book-stitching machine comprising, in combination, stitching means, a main pivotal sheet saddle arranged to move to and from said stitching means, an auxiliary sheet saddle secured to said main saddle to form a lateral extension thereof, a sheet-lay to locate a sheet laid upon said auxiliary saddle, reciprocatory means for transferring the sheet from said auxiliary saddle to said main saddle, during the movement of said saddles, sheet retaining means arranged to press the transferred sheet upon said main saddle prior to the idle return movement of said sheet-transferring means, a guide member for piloting said sheet-transferring means in its return movement beneath a second sheet laid upon said auxiliary saddle, and secondary sheet-engaging means arranged to engage the sheet retained upon said main saddle.

23. A book-stitching machine comprising, in combination, stitching means, a main pivotal sheet saddle arranged to move to and from said stitching means, an auxiliary sheet saddle secured to said main saddle to form a lateral extension thereof, a sheet-lay to locate a sheet laid upon said auxiliary saddle, a reciprocatory sheet gripper slidably mounted upon said auxiliary saddle, driving means mounted independently of said saddles, to reciprocate said sheet gripper longitudinally of said saddles thus to engage the sheet laid upon said auxiliary saddle and effect the transfer thereof to said main saddle, loose coupling means to establish driving connection between said sheet gripper and said driving means, pivotally mounted blade springs associated with said main saddle and arranged to retain on the

latter the sheet transferred from said auxiliary saddle, means for displacing said sheet retaining springs from said sheet prior to the stitching of the sheet, and secondary sheet-engaging and smoothing members arranged in the path of travel of said main saddle to engage the sheet thereon prior to the displacing movement of said sheet-retaining springs.

24. A book-stitching machine comprising, in combination, stitching means, a main pivotal sheet arranged to move to and from said stitching means, an auxiliary sheet saddle mounted upon a pivotal axis common to said main carrier, means for moving said auxiliary saddle synchronously with said main saddle through part of the movement of the latter, a sheet-lay to locate a sheet laid upon said auxiliary saddle, reciprocatory means for transferring the sheet from said auxiliary saddle to said main saddle during the movement of said saddles, sheet-retaining means arranged to press the transferred sheet upon said main saddle prior to the idle return movement of said sheet-transferring means, a guide member for piloting said sheet-transferring means in its return movement beneath a second sheet laid upon said auxiliary saddle, and secondary sheet-engaging means arranged to engage the sheet retained upon said main saddle.

25. A book-stitching machine comprising, in combination, stitching means, a main pivotal sheet arranged to move to and from said stitching means, an auxiliary sheet saddle mounted upon a pivotal axis common to said main carrier, means for moving said auxiliary saddle synchronously with said main saddle through part of the movement of the latter, a sheet-lay to locate a sheet laid upon said auxiliary saddle, a reciprocatory sheet gripper slidably mounted upon said auxiliary saddle, driving means mounted independently of said saddles to reciprocate said sheet gripper longitudinally of said saddles, thus to engage the sheet laid upon said auxiliary saddle and effect the transfer thereof to said main saddle, loose coupling means to establish driving connection between said sheet gripper and said driving means, pivotally mounted blade springs associated with said main saddle and arranged to retain on the latter the sheet transferred from said auxiliary saddle, means for displacing said sheet retaining springs from said sheet prior to the stitching of the sheet, and secondary sheet-engaging and smoothing members arranged in the path of travel of said main saddle to engage the sheet thereon prior to the displacing movement of said sheet retaining springs.
